UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL SYSTEM.

1,421,243.

Specification of Letters Patent. Patented June 27, 1922.

Application filed April 4, 1919. Serial No. 287,561.

To all whom it may concern.

Be it known that I, HENRY D. JAMES, a citizen of the United States, and a resident of Edgewood Park, in the county of Allegheny and State of Pennsylvania, have invented a new and useful Improvement in Control Systems, of which the following is a specification.

My invention relates to motor-control systems and particularly to systems of the character set forth in my copending application, Serial No. 236,937, filed May 27, 1918, in which the accelerating resistor is controlled by an energizing coil, or energizing coils, responsive to the voltage of the resistor.

An object of my invention is to provide an improved control system of the above-described character.

A further object of my invention is to provide a system of the above-described nature which shall be especially adapted for push-button control.

Another object of my invention is to provide such a system with which it shall be possible to control the speed of the motor.

Other objects of my invention will appear in connection with the subjoined description.

I preferably employ a relay of the type forming the subject-matter of a copending application by De Camp, Serial No. 241,259, filed June 21, 1918, and assigned to the Westinghouse Electric & Manufacturing Co. This relay is provided with a pair of coils one of which may be made responsive to the voltage of the resistor and the other be independent thereof. The coils control a main armature and a plurality of auxiliary armatures, the former of which controls the operation of the latter and also the contactor that is adapted to close the motor circuit.

I may arrange to close initially the circuit of either coil by means of a push-button. The coil circuit may then be automatically maintained closed, irrespective of the release of the push-button, or it may be adapted to be reopened upon the release of the push-button. In the former case, the initially operating coil should preferably be the one that is responsive to the voltage of the resistor. In the latter case, it should preferably be the other coil. In the former case, the motor will proceed to accelerate in accordance with predetermined conditions, as described in my above-referred to copending

application, the second coil becoming operative to maintain the resistor-short-circuiting contactors closed upon the resistor becoming short-circuited. In the latter case, the initially operating coil may be so designed as to prevent the resistor-short-circuiting contactors from closing, thus providing for operating the motor at slow speed so long as the push-button remains operative, but permitting the other coil to become effective to accelerate the motor as soon as the push-button is released.

In the accompanying drawings, Figures 1 and 2 are, respectively, a side and an end elevational view of a relay of the type constituting the subject-matter of the aforementioned application by De Camp. Fig. 3 is a diagrammatic view of circuits and apparatus illustrating one embodiment of my invention, and Fig. 4 is a similar diagrammatic view illustrating another embodiment of my invention.

As my invention is of particular value in a system employing the above-referred-to De Camp relay, illustrated in Figs. 1 and 2, it will conduce to clearness to describe this relay first.

An insulating panel 29 carries two brackets 30 and 31 supporting coils 22 and 23 which, when energized by current flowing through them, produce magnetic fields for attracting an armature 32 and any desired number of additional armatures 33. A compression spring 36 is adjustably mounted upon a non-magnetizable rod 37, slidably mounted in arms 38 and 39, which are rigidly connected to, or constitute integral parts of, the bracket 31. The arm 38 serves also as a pole piece for the armature 32, and the arm 39 as a pole piece for the armatures 33. A bar 40 is rigidly connected to the rod 37 and normally engages the armatures 33. The spring 36 thus normally maintains the armatures 33 in their open positions, with the members 41, which are carried by these armatures, in contact with the pole piece 39. The members 41 are preferably of non-magnetizable material to prevent "freezing."

The armature 32 is provided with ears or lugs 42, which are pivotally mounted upon the bracket 30, and is normally maintained in contact with one end of the rod 37 by a weak spring 43. The bracket 30 supports a non-magnetizable, U-shaped member 44

2
between the arms of which are pivotally mounted the armatures 33, which carry, respectively, the movable contact members 45, 46 and 47 of relays 25, 26 and 27. The corresponding stationary contact members 48, 49 and 50 are mounted upon the insulating panel 29.

10 Springs 51 are attached to longitudinally adjustable members 52 and to the other ends of the members 41. The pole piece 39 is provided with longitudinally adjustable members 53 to regulate air gaps 70 between these members and the corresponding armatures. By means of this adjustment, or by means of 15 the members 52, which control the tension of the springs 51, the action of the magnetic flux produced by the coils 22 and 23 may be so regulated that the armatures 33 will be operated in proper sequence.

20 The armature 32 is provided with an extension 54, preferably of insulating material, which carries a contact member 55 for co-operating with stationary contact members 57 mounted upon the insulating panel 29. As 25 shown in Fig. 1, the contact members 55 and 57 are open when the armature 32 occupies its normal or open position.

The operation may be briefly described as follows. Upon current flowing through the 30 coil 22, a magnetic field is produced which causes the armature 32 to be attracted toward the pole piece 38. The force of the spring 36 is thereupon overcome, and the bar 40 is moved out of engagement with the armatures, the stop members 41 of which are, nevertheless, maintained in engagement with the pole piece 39 until the flux of the magnetic field successively becomes sufficiently 35 low to permit the springs 51 to successively 40 actuate the movable contact members 45, 46 and 47, thereby to close the relays 25, 26 and 27. In the event that the magnetic field becomes too weak to hold the armature 32 in its elevated position, the spring 36, becoming 45 released, will separate the movable from the stationary contact members. Actuation of the armature 32, of course, effects corresponding actuation of the contact member 55.

50 I shall now describe the invention illustrated in Fig. 3. A motor, the armature of which is shown at 1 and the shunt-field-magnet winding at 2, is connected between line conductors 3 and 4, with a regulating resistor 6 normally in series with the armature 1. Although I have here shown, for purposes of illustration, a shunt-wound motor, it will be understood that my invention is equally applicable to a series or a compound-wound 55 motor. The circuit of the motor is adapted to be closed by a line contactor 5, having an energizing coil 8, the circuit of which is controlled by the contact members 55 and 57 and by a pair of push-buttons respectively designated, to indicate their function, as "start" 60

and "stop". The contactor 5 is provided with a switch 66 mechanically connected thereto for shunting the "start" push-button.

One or more contactors 10, 11 and 12 (three are shown) control the short-circuiting of successive portions 13, 14 and 15 of the 70 regulating resistor 6, through the medium of energizing coils 19, 20 and 21. The coil 22 is connected across the terminals of the resistor 6 at 79 and 80. The energization of 75 the coil 22 causes the successive closing of the relays 25, 26 and 27, as above described, in accordance with the strength of the current passing through the coil 22. The coil 19 is connected in a circuit leading from the line conductor 3, by way of a conductor 28, the coil 19, the relay 25, the "start" push-button switch or the switch 66, and the "stop" push-button switch, to the line conductor 4. The coils 20 and 21 are similarly connected to 80 the relays 26 and 27, in parallel to the coil 19 and the relay 25. The circuit of the coil 23 is closed at the same time as that of the coil 21 by the relay 27, and comprises a resistor 24.

90 The operation may be described as follows: Upon the actuation of the "start" push-button, a circuit is established from the line conductor 3, through the armature 1 to the junction point 79, and from there through the coil 22, by way of a conductor 74, through the "start" and "stop" push-button switches to the point 80, which is connected to the line conductor 4. The coil 22 thereupon becomes energized, effecting the actuation of 100 the armature 32 into engagement with the pole piece 38 (Fig. 1). The switches 55 and 57 thereupon become closed, establishing a circuit from the line conductor 3, by way of the conductor 28, through the coil 8, the contact members 55 and 57, by the conductor 74, through the "start" and "stop" push-button switches, to the junction point 80 and from there to the line conductor 4. The coil 8 becomes thereby energized to effect the 105 closing of the contactor 5 and the switch 66 which is mechanically connected thereto.

110 The "start" push-button switch may now be released, a holding circuit for the coil 22 being now created from the line conductor 3, through the armature 1, the junction point 79, the coil 22, the switch 66 and the "stop" push-button switch to the junction point 80.

115 The line contactor 5 establishes the motor circuit from the line conductor 3, through the armature 1, the resistor 6 and the line contactor 5 to the junction point 80, which is connected to the line conductor 4. The motor will accordingly commence to accelerate.

120 The coil 22 will thereupon become subjected to the voltage drop between the junction points 79 and 80 across the resistor 6. As the motor accelerates and the current 125

begins to die down, the magnetic flux set up by the coil 22 becomes weakened. After a time, when the flux has decreased to a predetermined value, due to the decrease in 5 voltage across the resistor 6, the spring 51 (Fig. 1), which is attached to the armature 33 of the relay 25, will overcome the forces exerted by the flux of this field, so that the relay 25 will become closed. The time when 10 this operation will occur will depend upon the size of the air gap 70 and the tension of the spring 51. The relays 26 and 27, however, remain open.

The closing of the relay 55 establishes 15 the above-described circuit of the coil 19. The contactor 10 is thereupon closed by its coil 19 to short-circuit the section 13 of the resistor 6. The motor then further accelerates and, by decreasing the voltage across 20 the junction points 79 and 80 of the resistor 6, the magnetic field in the neighborhood of this coil is further weakened, which permits the closing of the second relay 26. A circuit is then completed from the line 25 conductor 3 by the conductor 28, through the coil 20, the relay 26, the switch 66 and the "stop" push-button switch to the junction point 80, which is connected to the line conductor 4. The coil 20, thus becoming 30 energized, causes the closing of the contactor 11 and the consequent shunting of the second portion 14 of the resistor 6. After the motor has accelerated further, the magnetic field surrounding the coil 22 is again 35 weakened and the relay 27 is closed, creating a circuit extending from the line conductor 3, by the conductor 28, through the coil 21 and the relay 27 to the switch 66, which is connected to the line conductor 4, 40 thereby causing the closing of the contactor 12 and the shunting of the third portion 15 of the resistor 6. The whole resistor is then shunted from the armature circuit, and the armature 1 is connected directly across 45 the line.

The shunting of the entire resistor 6 de-energizes the coil 22, which would release the armature 32 and cause the relays 25, 26 and 27 to be reopened, thus resulting in 50 de-energization of the coils 19, 20 and 21 and the consequent reinsertion of the resistor 6 into the armature circuit, except for the coil 23 which becomes energized at the same time as the coil 21, upon the 55 closing of the relay 27. The circuit of this coil extends from the line conductor 3, by the conductor 28, through the resistor 24, the coil 23, the relay 27, the switch 66 and the "stop" push-button switch, to the junction 60 point 80, which is connected to the line conductor 4. The coil 23 becomes thus energized by line voltage to maintain the armature 32 closed and, therefore, to permit the relays 25, 26 and 27 to occupy their closed 65 positions.

To stop the motor, it is necessary to actuate the "stop" push-button switch, which will effect the de-energization of the control circuits. The circuit of the coil 23 will become opened, the armature 32 will become 70 released, the spring 36 (Fig. 1) will open the relays 25, 26 and 27 to effect the opening of the circuits of the coils 19, 20 and 21, the contactors 10, 11 and 12 will become opened to reinsert the resistor 6 into the 75 armature circuit, and the contact members 55 and 57 will effect the opening of the circuit of the coil 8 to cause the contactor 5 to open the motor circuit.

As it is fully explained in my copending 80 application, Serial No. 260,949, filed Nov. 4, 1918, it will be impossible to start the motor until the contact members 55 and 57 have been closed to close the circuit of the coil 8. So long as the contact members 55 and 57 85 are open, the contactors 10, 11 and 12 are open and the resistor 6 is, therefore, in circuit with the armature 1. It is, therefore, impossible to effect the closing of the contactor 5 while the resistor 6 is short-circuited, so that the armature 1 is protected 90 from being thrown directly across the line conductors 3 and 4.

By means of this arrangement of circuits, I provide a novel accelerating system that 95 is especially adapted for push-button control and which protects the motor from possible injury due to the armature being directly connected to the line.

In this system, the armature 32 is adapted 100 to be initially operated by the coil 22. This is by no means essential, as the armature 32 may be initially actuated by the other coil 23. One way of accomplishing this result I have illustrated in connection with 105 the system of Fig. 4.

A further change has been made in the system of Fig. 4 in that the circuits are so connected that the "start" push-button cannot be shunted, as by means of the switch 110 66 shown in Fig. 3. The "start" push-button switch is adapted initially to close the circuit of the coil 23 to effect the operation of the armature 32, and the coil 23 is so designed that, irrespective of the current 115 conditions of the motor, it will maintain the relays 25, 26 and 27 open. Upon the release of the "start" push-button switch the coil 23 will become de-energized, transferring the control of the armature 32 and 120 the relays 25, 26 and 27 to the coil 22, which is connected across the resistor 6. So long as the "start" push-button switch is maintained closed, therefore, the resistor 6 is 125 maintained in circuit with the armature 1 and not until the "start" push-button switch is released will the coil 22 be rendered effective to effect the acceleration of the motor.

This will be made clear in connection 130

with the following description of the operation. Upon the actuation of the "start" push-button switch, a circuit is established from the line conductor 3, through the coil 23, and the "start" and "stop" push-button switches, to the line conductor 4. The coil 23 will thereupon become energized by line voltage to effect the actuation of the armature 32 into engagement with the pole piece 38 (Fig. 1). The contact members 55 and 57 will thereupon become closed to establish the circuit for the coil 8 from the line conductor 3, by the conductor 28, the coil 8, the contact members 55 and 57 and the "stop" push-button switch, to the line conductor 4. The contactor 5 will thereupon close the motor circuit, which extends from the line conductor 3, through the armature 1, the resistor 6 and the contactor 5, to the line conductor 4.

Although the armature 32, when actuated into engagement with the pole piece 38, effects the release of the armatures 33 from the restraining influence of the bar 40 (Fig. 1), these armatures 33 will be maintained in the illustrated position (Fig. 1) by the coil 23. This is because the coil 23 is energized from the line conductors 3 and 4 and is, therefore, subjected to constant voltage, unlike the coil 22, which, being connected across the resistor 6, is subjected to a decreasing voltage. The motor may therefore be operated at slow-speed so long as the "start" push-button switch is maintained closed.

When it is desired to accelerate the motor, all that is necessary is to release the "start" push-button switch. The armatures 32 and 33 are thereupon released from the control exercised over them by the coil 23 and become subjected, instead, to the influence of the coil 22 which is connected across the resistor 6. In substantially the same manner as above-described in connection with the description of the operation of the system of Fig. 3, the relays 25, 26 and 27 will thereupon become closed, in accordance with the decreasing voltage of the resistor 6, to effect the closing of the contactors 10, 11 and 12 and the consequent short-circuiting of the resistor portions 13, 14 and 15. Upon the short-circuiting of the last resistor portion 15, the coil 22, of course, becomes deenergized, but the coil 23 is again brought into play to maintain the armature 32 in its actuated position by a circuit, which is closed at the time of the closing of the relay 27, from the line conductor 3, through the coil 23, the resistor 24, the relay 27 and the "stop" push-button switch, to the line conductor 4. Though the coil 23 was enabled to maintain the armatures 33 in open position initially, it is designed so as not to reopen these armatures once they have become closed. The motor therefore

will continue to operate at its normal speed until the "stop" push-button switch is actuated to effect the opening of the control circuits in a manner substantially the same as that described above.

Though my invention is particularly adapted for push-button control, it is sometimes desirable to operate a system of the character illustrated in Fig. 4 by an ordinary master switch, such as that shown at 7 and adapted to engage contact members 16 and 17. The contact member 17 is longer than the contact member 16 so that, initially, when the master switch 7 is actuated into engagement with the contact members 16 and 17, an operation similar to that described above, in connection with the description of the control exercised by the "start" push-button switch, will take place. This is because the "start" push-button switch and the contact member 16 are connected in parallel to each other and in series with the coil 23. Upon further actuation of the master switch 7, so as to break the engagement of the master switch and the contact member 16, the armatures 32 and 33 will come under the control of the coil 22, the coil 23 becoming open at the contact member 16, the operation in other respects being the same as that above described. In this manner, the motor may ordinarily be controlled by the "start" and "stop" push-button switches and, at other times, when desired, by the master switch 7.

It will be noted that I have provided a novel motor-accelerating system that is especially adapted for push-button control. I have shown one method for effecting the speed control of such a system. Other methods for obtaining this result will occur to those skilled in the art and are intended to be covered by the annexed claims. It is understood that these claims are to be construed broadly except insofar as limitations may therein be specifically imposed.

I claim as my invention:

1. The combination with an electric motor having a resistor associated therewith and a switch for short-circuiting said resistor, of a pair of coils for controlling said switch, one of said coils being responsive to the voltage of said resistor and the other of said coils being adapted to control said switch upon the short-circuiting of said resistor, a manually-operable switch for initially establishing the circuit of one of said coils, and a manually-operable switch for opening the circuit of one of said coils.

2. The combination with an electric motor having a resistor associated therewith, a switch for short-circuiting said resistor, and a coil in parallel relation to said resistor for controlling said switch, of a switch for initially establishing the circuit of said coil, a coil for controlling said resistor switch upon

- the short-circuiting of said resistor, and a switch for opening the circuit of said second-named coil.
3. The combination with an electric motor 5 having an armature, a resistor in series therewith, and a switch for closing the circuit of said motor, of a switch for short-circuiting said resistor, an armature for controlling said switch having an actuating coil 10 in parallel relation to said resistor, a manually-operable switch for initially establishing the circuit of said coil, a coil for maintaining said armature in its actuated position upon the closing of said resistor switch, 15 and a manually-operable switch for opening the circuit of said second-named coil.
4. The combination with an electric motor having an armature, a resistor in series therewith, and a switch for closing the circuit of said motor, of a plurality of switches 20 for short-circuiting said resistor, an auxiliary armature for controlling each of said plurality of switches, a main armature for controlling said circuit-closing switch and 25 said auxiliary armatures, a coil for controlling all of said armatures and for maintaining said armatures in predetermined positions, irrespective of the current conditions of the motor, a manually operable switch for 30 closing the circuit of said coil and for opening the circuit of said coil except when it occupies its operative position, a coil connected across said resistor for controlling all of said armatures, and means for actuating 35 said auxiliary armatures to effect the closing of the corresponding short-circuiting switches in accordance with the current conditions of said motor when the circuit of said first-named coil is open.
- 40 5. The combination with an electric motor and a line switch and an accelerating switch therefor, of means for controlling the operation of said switches, said means comprising a relay and a switch for successively 45 rendering said relay responsive to line volt-
- age to effect the operation of said line switch and to the current traversing the motor circuit prior to the closing of said accelerating switch.
6. The combination with an electric motor 50 and an accelerating switch therefor, of means for controlling the operation of said switch, said means comprising a manually-operable switch and electro-responsive means so controlled by successive actuations of said 55 manually-operable switch as to be successively energized in accordance with line voltage and with the value of the current traversing the motor circuit, respectively, prior to the closing of said accelerating switch. 60
7. The combination with an electric motor, a line switch, and an accelerating switch therefor, of means for controlling the operation of said switches, said means comprising a plurality of armature members, electromagnetic means for controlling said members and manually-operable means for occupying a plurality of positions to effect the successive energization of said electromagnetic means in accordance with line voltage 65 and with the value of the current traversing the motor circuit, respectively, to effect the operation of said armature members. 70
8. The combination with an electric motor, a line switch therefor and a starting resistor, of an accelerating switch for controlling said resistor, a relay for successively effecting the operation of said line switch and said accelerating switch, in accordance 75 with line voltage and motor-circuit current 80 conditions, respectively, and manually operable means that must be successively actuated to closed and open positions before the relay is operative to effect the closing of the respective switches. 85

In testimony whereof, I have hereunto subscribed my name this 22nd day of March, 1919.

HENRY D. JAMES.
